UNITED STATES PATENT OFFICE.

THOMAS FRANCIS BRADY, OF KANSAS CITY, MISSOURI.

CARD-HOLDER.

1,148,887.

Specification of Letters Patent.

Patented Aug. 3, 1915.

Application filed May 19, 1914. Serial No. 839,613.

To all whom it may concern:

Be it known that I, THOMAS FRANCIS BRADY, a citizen of the United States, residing at Kansas City, in the county of Jackson and State of Missouri, have invented a new and useful Card-Holder, of which the following is a specification.

The invention relates to improvements in railway shipping card holders.

10 The object of the present invention is to improve the construction of card holders, and to provide a simple, inexpensive and efficient card holder of strong and durable construction, designed for use on railway cars for holding shipping and other cards, and adapted to enable a card to be readily placed in and removed from it, and capable of securely retaining the card in place to prevent accidental loss.

20 With these and other objects in view, the invention consists in the construction and novel combination of parts hereinafter fully described, illustrated in the accompanying drawing, and pointed out in the claims hereinafter appended; it being understood that various changes in the form, proportion, size and minor details of construction, within the scope of the claims, may be resorted to without departing from the spirit or sacrificing any of the advantages of the invention.

30 In the drawing: Figure 1 is an elevation of a railway card holder, constructed in accordance with this invention. Fig. 2 is a vertical sectional view on the line 2—2 of Fig. 1. Fig. 3 is a similar view on the line 3—3 of Fig. 1. Fig. 4 is a horizontal sectional view on the line 4—4 of Fig. 1. Fig. 5 is a reverse plan view of the card holder, the back being omitted.

40 Like numerals of reference designate corresponding parts in all the figures of the drawing.

45 In the accompanying drawing in which is illustrated the preferred embodiment of the invention, the card holder comprises an approximately U-shaped frame 1, designed to be constructed of any suitable material and mounted upon a back 2 and composed of spaced sides and a connecting end portion, the frame being closed at one end by the said end portion and open at the other end for the introduction and removal of a card 3. 50 The back 2 to which the frame is secured by screws 4 or other suitable fastening devices may consist of a block of wood or any other

suitable material, which is designed to be suitably fastened to the side of a freight or other car, but the frame may be secured directly to the car, the back 2 being omitted if desired. The sides of the frame are parallel and the ends are preferably straight, as shown, and the frame is provided at the end edges of its end and sides with inwardly projecting flanges 5 and 6 forming grooves 60 for the reception of the adjacent side edges of the car 3 and providing ways at opposite sides of the frame to enable the card to slide into and out of the same through the open end thereof.

70 The sides of the frame are provided adjacent to the open end of the said frame with opposite bearings 7 and 8 for the reception of terminal pivot portions 9 and 10 of an eccentric 11, and the said sides of the frame 75 are preferably enlarged at the bearings 7 and 8. The bearing 7 consists of a transverse opening, and the other bearing 8 is formed by a recess opening at the inner face of the side of the frame, as clearly shown in 80 Figs. 3 and 5 of the drawing. This construction permits the eccentric to be readily placed in and removed from the bearings when the frame 1 is detached. The eccentric, which extends across the frame adjacent to the open end thereof, is rounded, the pivot portions 9 and 10 being eccentrically arranged with relation to the round body portion of the eccentric, and the said pivot portion 10 is provided with an operating 90 arm 12, located beyond the adjacent side of the frame and adapted to be oscillated to partially rotate the eccentric for opening and closing the longitudinal grooves or ways of the frame. When the operating arm 12 95 is swung against the back 2, the eccentric is caused to project across the longitudinal grooves or ways 5, and it will either confine a card therein, or if the card should be of a length to extend beneath the eccentric, it 100 will be securely clamped against the back 2. The eccentric is also adapted to be rotated to carry it beyond the grooves or ways 5 to open the same.

105 The frame may consist of a casting or may be pressed out of malleable metal, and when constructed in this manner, the back, the flange, and the bearings for the eccentric will be formed by a suitable die. This will reduce the cost of the construction and 110 enable the device to be cheaply manufactured.

What is claimed is:—

1. A card holder comprising a frame having spaced sides provided with longitudinal ways, said frame being open at one end to permit a card to be introduced into the ways and the other end of the frame being closed and constituting a stop for the card, and an eccentric rod arranged between and extending across the space between the sides of the frame at the open end thereof, said eccentric rod being journaled in the sides of the said frame and rotatable to carry it into and out of the plane of the ways to confine or clamp a card therein and to release the same, and a handle provided on the rod for operating the same.
2. A card holder of the class described including a substantially U-shaped frame open at one end and provided at opposite sides with longitudinal ways, the sides of the frame being also enlarged adjacent to the open end of the same to form bearings, one

of the bearings comprising a recess opening at the inner face of the frame, a transversely disposed eccentric consisting of a round body, 25 portion extending across the open end of the frame and fitting between the said enlargements and having terminal pivot portions arranged in the said bearings, the said recess permitting the said pivot portions to be 30 placed in and removed from the bearings, the said eccentric being rotatable to project it into the plane of the grooves or ways and to carry it therefrom, and a handle connected with the pivot portion which is ar- 35 ranged in the open recess.

In testimony, that I claim the foregoing as my own, I have hereto affixed my signature in the presence of two witnesses.

THOMAS FRANCIS BRADY.
